(57) **CLAIM**

The ornamental design for a drywall corner trimming strip with beveled edge, as shown and described.

DESCRIPTION

FIG. 1 is a top front perspective view of a drywall corner trimming strip with beveled edge embodying my new design; FIG. 2 is a top rear perspective view thereof; FIG. 3 is a rear view as viewed from line 3-3 of FIG. 2; and, FIG. 4 is a front view as viewed from line 4-4 of FIG. 2. The openings and the fins in phantom lines form no part of the claimed design. The trimming strip is shown with portions cut away to indicate no specific length.
